AUTOGRAPHIC REGISTER AND THE LIKE

Arvid Lindquist, Copenhagen, and Paul de Waal,
Gentofte, DenmarkApplication December 15, 1945, Serial No. 635,222
In Denmark December 22, 1944

5 Claims. (Cl. 282—12)

1

This invention relates to autographic registers of the kind comprising a casing containing a pack of continuous stationary forms, which may be interfolded or interleaved so that carbon paper or the like may be introduced between the folds or leaves at a convenient point according to the number of copies required.

The casing is provided with an opening on one side thereof exposing a writing plate and the arrangement is such that one or more forms can be drawn out through a slot and pulled over the writing plate where the necessary inscription is made and the used form or forms, according to the number of copies made, are torn off.

In known constructions of registers of this kind, the folded forms from the supply pack are pulled over an edge of the writing plate and are arrested thereon by the fold catching against the edge of the plate and cannot be pulled further until a release mechanism has been operated to allow the fold to clear the edge of the plate.

It is usual to provide such known registers with strip release mechanism operated by a handle movable across the strip in opposition to the direction of travel and which causes a roller, carried by a link system formed as a parallelogram, to lift the fold of the strip clear of the edge of the plate. The usual arrangements of such mechanism necessitate a register of somewhat large dimensions.

The object of the invention is to provide an autographic register of the above type of such small dimensions that it may easily be carried in the pocket, without any decrease in the size of the usual pack or of the number of forms therein.

According to the invention an improved form of release mechanism is provided whereby the fold of the forms or strips is released from the edge of the writing plate by mechanism which is operated by the movement of a part of the register casing by hand. This arrangement has the advantage that a separate handle for the release of the strip is not required and therefore there is no risk of the release of the strip being maintained so long that it is not automatically stopped when it is moved forwards a distance corresponding to the distance between two adjacent fold lines. Preferably, as there is no operating handle, one or more resiliently or movably mounted pins are provided for preventing the forms from sliding back as hereinafter described.

To enable the invention to be fully understood

2

it will now be described by reference to the accompanying drawing, in which:

Fig. 1 is a plan view of an autographic register having one form of the invention applied thereto, and

Fig. 2 is a sectional view on line II—II of Fig. 1.

Fig. 3 is a view similar to Fig. 2 but showing the parts in a different position.

As shown, the apparatus comprises a casing

10 in which the supply pack is inserted, a part 2 of the casing being in the form of a flap movable about a hinge 3 and being held in the position shown in Fig. 2 by a spring (not shown). A writing plate 4 is fitted to the top of the casing and is hinged upon a spindle 5 mounted in the casing.

The writing plate 4 is provided with flanges 6 on two opposite sides thereof, and with guides 7 for the forms.

20 The flanges 6 are slotted at 8 and a member preferably in the form of a roller 9 extending transversely of the plate 4 is mounted therein, its ends being attached to links 10, one on each side of the plate, the ends of each links 10 being linked to a lever 11 pivoted in the casing at 12, a roller 13 being mounted between the pair of levers 11.

25 A spring 14 normally holds the parts in the position shown in Fig. 2. One set only of the 30 levers and links is shown, it being understood that another similar set is applied on the other side of the plate 4. The casing is fitted with an apertured cover plate (not shown) which is preferably slightly smaller than the size of the forms 35 so that a form on the writing plate is framed by the cover plate. The cover plate is attached to hinges 14a and fastening means are provided whereby the plate, when closed over the writing plate 4, exerts a slight pressure on the forms on 40 the writing plate.

45 Two pointed pins 15 are arranged on the plate 4 and are resiliently or movably mounted. These pins engage the forms when in position on the writing plate to prevent them from sliding back, and are so mounted that when the forms are pulled in the direction of the arrows, Fig. 2, the pins are swung below the plane of the writing plate 4.

50 The operation in the above described apparatus is as follows: Assuming that a pack of continuous folded forms is inserted in the supply compartment of the register and that the top form is pulled out over the writing plate 4 in the direction of the arrow Fig. 2, in the usual 55 manner, so that the first fold on the strip of

forms is arrested by the edge 16 of the plate 4.

The free end of the strip is passed through the guides 7 and the cover plate is closed down which presses the points of the pins 15 into the strip and prevents it from slipping back. The inscription is made on the form on the writing plate and the free end of the strip, which slightly projects at 18, is grasped and in so doing the fingers make contact with the hinged flap 2 and depress it. A slight depression 19 may be provided in the flap 2 adjacent to the point 18 as shown in Fig. 1 to assist the grasping of the end of the strip. On the depression of the flap 2 the linkage 11, 10 straightens, moving the roller 9 in its slots 8 into contact with the strip which lifts the fold of the strip clear of the edge of the plate 4. The roller 13 runs round the inside of the casing during this operation. This position is shown in Fig. 3. The strip can now be pulled freely in the direction of the arrow, Fig. 2, the pins 15 dropping down.

As the pulling of the strip proceeds the finger pressure on the flap 2 is removed and the spring (not shown) raises it and the linkage back into the position shown in Fig. 2. The roller 9 is thus moved back into the original position and the next fold on the strip of forms is arrested by the edge 16 of the plate 4. The used part of the strip can now be torn off at the first fold without dragging forward the next set of forms as will be understood. If carbon copies are required, a carbon sheet having strengthening strips provided with holes fitting over pins 20 provided on the writing plate 4 may be used. Any usual form of carbon copying device may be used with the register. Various modifications of the invention are possible.

In the arrangement described, the motion of the movable flap 2 of the casing in one direction is translated into a movement in a direction at right-angles thereto.

The casing 1 is shown as rounded, but it may be of angular shape with a rounded or other shaped movable part or flap for actuating the release mechanism.

We claim:

1. In an autographic register, a casing for receiving a pack of folded forms and having a top wall a part of which forms a writing table, said top wall having a slot therein through which folded forms are drawn from within said casing and providing an edge for engagement of a fold in said forms for holding said forms when a fold engages said edge, a bar reciprocably mounted beneath said table adjacent said edge and movable toward the same to release form folds therefrom, said top wall including a portion forming part of an end wall on said casing opposite the end having said slot, means mounting said end wall part on said casing for pivotal movement inwardly of said casing and engageable by the fingers of a hand on normal approach toward a form on said table to tilt said wall part inwardly of said casing simultaneously with grasping of the end of a form on said table with the fingers of one hand, and extensible linkage means mounted in said casing having at one end a connection with said bar and at the other end means engageable by the pivoted wall part, said extensible linkage translating into reciprocal motion of said bar relatively parallel to said top wall the motion of said end wall part relatively normal to said top wall whereby the grasping of the end of a form on said table will be accompanied automatically and simultaneously by a releasing of a fold on the other end of the form from the said edge by the use of the fingers of one hand, and pin means pivotally mounted on said casing beneath said top wall and projectable through said top wall for engagement with forms positioned on said top wall, said pin means being so pivotally mounted as to release a form while being withdrawn from its position on said writing table but engageable with said form to prevent return of the form into said casing through said slot.

a releasing of a fold on the other end of the form from the said edge by the use of the fingers of one hand.

2. In an autographic register, a casing for receiving a pack of folded forms and having a top wall a part of which forms a writing table, said top wall having a slot therein through which folded forms are drawn from within said casing and providing an edge for engagement of a fold in said forms for holding said forms when a fold engages said edge, a bar reciprocably mounted beneath said table adjacent said edge and movable toward the same to release form folds therefrom, said top wall including a portion forming part of an end wall on said casing opposite the end having said slot, means mounting said end wall part on said casing for pivotal movement inwardly of said casing and engageable by the fingers of a hand on normal approach toward a form on said table to tilt said wall part inwardly of said casing simultaneously with grasping of the end of a form on said table with the fingers of one hand, and jack-knife extensible linkage means mounted in said casing having at one end a connection with said bar and at the other end means engageable by the pivoted wall part, said extensible linkage translating into reciprocal motion of said bar relatively parallel to said top wall the motion of said end wall part relatively normal to said top wall whereby the grasping of the end of a form on said table will be accompanied automatically and simultaneously by a releasing of a fold on the other end of the form from the said edge by the use of the fingers of one hand.

3. In an autographic register, a casing for receiving a pack of folded forms and having a top wall a part of which forms a writing table, said top wall having a slot therein through which folded forms are drawn from within said casing and providing an edge for engagement of a fold in said forms for holding said forms when a fold engages said edge, a bar reciprocably mounted beneath said table adjacent said edge and movable toward the same to release form folds therefrom, said top wall including a portion forming part of an end wall on said casing opposite the end having said slot, means mounting said end wall part on said casing for pivotal movement inwardly of said casing and engageable by the fingers of a hand on normal approach toward a form on said table to tilt said wall part inwardly of said casing simultaneously with grasping of the end of a form on said table with the fingers of one hand, extensible linkage means mounted in said casing having at one end a connection with said bar and at the other end means engageable by the pivoted wall part, said extensible linkage translating into reciprocal motion of said bar relatively parallel to said top wall the motion of said end wall part relatively normal to said top wall whereby the grasping of the end of a form on said table will be accompanied automatically and simultaneously by a releasing of a fold on the other end of the form from the said edge by the use of the fingers of one hand, and pin means pivotally mounted on said casing beneath said top wall and projectable through said top wall for engagement with forms positioned on said top wall, said pin means being so pivotally mounted as to release a form while being withdrawn from its position on said writing table but engageable with said form to prevent return of the form into said casing through said slot.

4. In an autographic register, a casing for receiving a pack of folded forms and having a top wall a part of which forms a writing table, said top wall having a slot therein through which folded forms are drawn from within said casing and providing an edge for engagement of a fold in said forms for holding said forms when a fold engages said edge, a bar reciprocably mounted beneath said table adjacent said edge and movable toward the same to release form folds therefrom, said top wall including a wall extending transversely across said casing and formed to provide an end portion of said top wall and a part of an end wall on said casing opposite the end having said slot, means mounting said wall part on said casing for pivotal movement inwardly of said casing engageable by the fingers of a hand on normal approach toward a form on said table to tilt said wall part inwardly of said casing simultaneously with grasping of the end of a form on said table with the fingers of one hand, and extensible linkage means mounted in said casing having at one end a connection with said bar and at the other end means engageable by the pivoted wall part, said extensible linkage translating into reciprocable motion of said bar relatively parallel to said top wall the motion of said end wall part relatively normal to said top wall whereby the grasping of the end of a form on said table will be accompanied automatically and simultaneously by a releasing of a fold on the other end of the form from the said edge by the use of the fingers of one hand.

5. In an autographic register, a casing for receiving a pack of folded forms and having a top wall a part of which forms a writing table, said top wall having a slot therein through which folded forms are drawn from within said casing and providing an edge for engagement of a fold in said forms for holding said forms when a fold en-

gages said edge, a bar reciprocably mounted beneath said table adjacent said edge and movable toward the same to release form folds therefrom, said top wall including a wall extending transversely across said casing and formed to provide an end portion of said top wall and a part of an end wall on said casing opposite the end having said slot, means mounting said wall part on said casing for pivotal movement inwardly of said casing engageable by the fingers of a hand on normal approach toward a form on said table to tilt said wall part inwardly of said casing simultaneously with grasping of the end of a form on said table with the fingers of one hand, a first pair of arms pivotally mounted within said casing, one arm of said pair being adjacent each of opposite sides of said casing, said arms having one end thereof engageable by said wall part upon movement thereof inwardly of said casing to rotate said arms about their pivots, and a second pair of arms positioned within said casing one each of said arms engaging the free end of one each of said first arms and the opposite end engaging said bar for reciprocation thereof relatively parallel to said top wall upon movement of said wall part relatively normal to said top wall.
